(57) CLAIM

What is claimed is the ornamental design for a tattoo needle holder, as shown and described.

DESCRIPTION

FIG. 1 illustrates a top perspective view of a new and ornamental tattoo needle holder;

FIG. 2 illustrates a bottom perspective view thereof;

FIG. 3 illustrates another top perspective view thereof;

FIG. 4 illustrates a top view thereof;

FIG. 5 illustrates a bottom view thereof;

FIG. 6 illustrates a left-side view thereof;

FIG. 7 illustrates a front view thereof; and,

FIG. 8 illustrates a rear view thereof.

The broken lines in the figures depict portions of the tattoo needle holder that form no part of the claimed design.

1 Claim, 7 Drawing Sheets
